United States Patent

Des. 234,729
Patented Apr. 1, 1975

234,729

UMBRELLA FRAME

Heinz Weber, Hilden, Germany, assignor to
Bremshy AG, Solingen, Germany

Filed Jan. 27, 1972, Ser. No. 221,209

Term of patent 14 years

Int. Cl. D3—03

U.S. Cl. D88—3 R

FIG. 1

FIG. 2

FIG. 3

FIG. 4

FIG. 1 is a bottom perspective view of an umbrella frame in a partially open position showing my new design;

FIG. 2 is a side elevational view thereof wherein the front and rear rib pairs have been omitted for ease of illustration;

FIG. 3 is a side elevational view thereof in a fully open position; and

FIG. 4 is a top plan view thereof.

I claim:

The ornamental design for an umbrella frame, as shown and described.
